UNITED STATES PATENT OFFICE.

FRANCIS McNAMARA, OF NEW ROCHELLE, NEW YORK.

MULTIPLE PIPE-FITTING.

1,362,718.

Specification of Letters Patent. Patented Dec. 21, 1920.

Application filed January 11, 1919. Serial No. 270,763.

To all whom it may concern:

Be it known that I, FRANCIS McNAMARA, a citizen of the United States, residing at New Rochelle, in the county of Westchester 5 and State of New York, have invented new and useful Improvements in Multiple Pipe-Fittings, of which the following is a specification.

The present invention relates to improvements in fittings for drainage pipe systems, 10 and particularly to a fitting intended to form a portion of a main service stack and to have a plurality of fixtures connected therewith.

It has been heretofore proposed to provide a fitting of this general character for household purposes adapted to have, for example, a closet, lavatory, and a bath tub connected thereto. With the earlier structures for this purpose, however, trouble has been experienced due to the fact that the flow through the main branch or closet connection of the fitting would cause a siphoning of the traps provided for preventing the 25 escape of gas through the lavatory and bath tub. With the earlier constructions also there was apt to be more or less of a siphoning action through the branches connecting the stack member with the lavatory and tub 30 due to the flow through the main stack.

The object of the present invention is to provide a fitting which may be readily connected with a plurality of fixtures and in which the objections hereinbefore referred 35 to incident to earlier constructions will be entirely avoided.

In the accompanying drawings,—

Figure 1 is an elevation of a fitting embodying the present invention.

Fig. 2 is a plan, partly in section, on the line 2—2 of Fig. 1.

Fig. 3 is a sectional view on the line 3—3 of Fig. 2.

Fig. 4 is a section on the line 4—4 of Fig. 1.

Referring to the drawings, it will be seen that the fitting comprises a main body section 1 adapted to have its ends connected with the members of the main stack of a 50 drainage system, in the ordinary manner, and a relatively large lateral branch 2 that is adapted for connection with a closet.

The branch 2 is shown as extending from the body 1 at an angle of substantially ninety

degrees and is, as usual, of relatively large 55 diameter.

The body 1 has a portion of its side wall deflected laterally to provide a pocket-like enlargement 3 thereof adjacent its upper end, and at one side of the main branch 2. 60 As shown in the drawings, this pocket-like enlargement is arranged eccentric to the main passage through the body 1 and is so positioned that it extends a considerable distance above the plane of the branch 2. Said 65 lateral enlargement of the body 1 constitutes in effect a second branch of the fitting, and in said deflected wall are formed two internally threaded passages 4, 5, adapted to be respectively connected with the drain pipes 70 of a lavatory and bath tub, or other fixtures. The parts are so arranged that the outlets from the passages 4, 5 are situated entirely above the plane of flow through the main lateral branch 2 so that such flow will not 75 exert a siphoning action on the pipes connected with said branch outlets in the manner that it would if it passed directly across them.

The surfaces surrounding the outer ends 80 of the passages 4, 5 are arranged in a plane inclined to the body of the fitting and made smooth so that branch pipes may be readily and securely connected thereto.

It will be seen that the pocket formed in 85 the body of the fitting is also situated at one side of the direct passage through the body 1, so that an air chamber is in effect provided between the outlet ends of the passages 4, 5 and the column of water flowing 90 through the stack.

The manner of using and the advantages incident to a fitting constructed as above described and as shown in the drawings, will be readily appreciated. It will be seen that 95 the fitting may be employed in an ordinary stack construction and that the fixtures connected with the branch pipes 4, 5 will be entirely relieved from any siphoning action due to the flow through either the body 1 or 100 the main lateral branch 2.

Having thus described the invention what is claimed is:

A drainage system pipe fitting comprising a body adapted to form part of a stack 105 and having a portion of the wall of the passage therethrough deflected and enlarged to form a chamber adjacent the upper end

of the body at one side and eccentric to the line of flow through said body, the body member having interiorly-threaded passages or branches formed directly in the laterally deflected wall of said enlargement, and a main branch communicating with the passage through the body to one side of said

enlarged portion thereof, the said lateral branches extending from the stack member above the plane of flow through the stack member and the main branch. 10

In testimony whereof I have hereunto set my hand.

FRANCIS McNAMARA.
